(57) **CLAIM**

The ornamental design for a computer mouse, as shown and described.

DESCRIPTION

FIG. 1 is a front top perspective view of a computer mouse showing of my new design;

FIG. 2 is a front bottom perspective view thereof;

FIG. 3 is a rear top perspective view thereof;

FIG. 4 is a top plan view thereof;

FIG. 5 is a bottom plan view thereof;

FIG. 6 is a left-side elevational view thereof;

FIG. 7 is a right-side elevational view thereof;

FIG. 8 is a front elevational view thereof; and

FIG. 9 is a rear elevational view thereof.

FIG. 10 is a front top perspective view of a second embodiment of the present invention;

FIG. 11 is a front bottom perspective view thereof;

FIG. 12 is a rear top perspective view thereof;

FIG. 13 is a top plan view thereof;

FIG. 14 is a bottom plan view thereof;

FIG. 15 is a left-side elevational view thereof;

FIG. 16 is a right-side elevational view thereof;

FIG. 17 is a front elevational view thereof; and,

FIG. 18 is a rear elevational view thereof.
